UNITED STATES PATENT OFFICE

WILLIAM R. HOWARD, OF WASHINGTON, DISTRICT OF COLUMBIA, ASSIGNOR TO UNIVERSAL OIL PRODUCTS COMPANY, OF CHICAGO, ILLINOIS, A CORPORATION OF SOUTH DAKOTA

TREATMENT OF HYDROCARBONS

Application filed February 21, 1927, Serial No. 169,774. Renewed February 4, 1931.

The present invention relates to improvements in the art of conversion of heavier hydrocarbons into lighter hydrocarbons, but more particularly to a process wherein the heavier ends or residue are so processed as to remain in a liquid form and yet yield a greater amount of lighter hydrocarbons, such as gasoline and the like.

In the cracking of hydrocarbon oils of the present time, it has been experienced that a crude oil of 20° Baumé gravity may be converted into 65-75% more or less, of light distillates, such as gasoline, and the remainder into solid coke, except for a small percentage of gas. It has also been experienced that this same crude may be converted into 75-85% more or less, of a similar light distillate, 5-10% more or less, into heavy residual oil, and the balance into solid coke, with the exception of the same small percentage of gas.

One of the objects of the present invention is to convert substantially the entire crude into liquid products wherein the overhead light distillates comprises the greater percent, and the remaining residuum is a liquid product having commercial value as fuel oil free from coke.

Other objects and advantages will be more completely apparent from the following description.

In the drawing, the single figure is a side elevational view showing diagrammatically apparatus for carrying out the invention.

Referring more in detail to the drawing, 1 represents a feed pump for forcing the charging stock through line 2 controlled by valve 2' into cracking tube 3 mounted in furnace 4. Line 5 is a transfer line from the cracking tube controlled by valve 5', into expansion chamber 6. From the top of expansion chamber 6, a vapor line 7, provided with valve 8, leads to the dephlegmator 9 and from the top of the dephlegmator line 10, provided with valve 11, leads to water cooled condenser 12, continuing through rundown line 13, controlled by valve 14, into receiver 15. Receiver 15 may be provided with a gas outlet at the top in the form of pipe 16, controlled by valve 17, and near the bottom thereof pipe 18, controlled by valve 19, for

the withdrawal of the condenser liquids. Line 20, controlled by valve 21, is a bottom drawoff for receiver 15.

From the side of expansion chamber 6 at different levels are outlet pipes 22, 23 and 24, controlled by valves 25, 26 and 27, respectively, running to a common line 28, which continues into mixing chamber 29. At the bottom of expansion chamber 6 an additional residuum drawoff 30 may be provided, which enters line 28 through valve 31; this drawoff 30 also has an outlet 32, controlled by valve 33, for withdrawing residuum from the system to a supply tank (not shown).

To the bottom of dephlegmator 9 may be connected the reflux leg 34 which may communicate with mixing chamber 29. Mixing chamber 29 may be provided with a stirring mechanism 35 and means for revolving same at 36. From the top of mixing chamber 29 a relief vapor line 37, in which may be interposed valve 37', leads back to dephlegmator 9. From the bottom of mixing chamber 29 the suction line 38 controlled by valve 38' leads to pump 39 for discharging a portion 75 of the contents of the mixing chamber through line 40 into expansion chamber 6.

The charging stock, if desired, may be delivered through line 41, through heat exchanger 42, here shown located in the top of dephlegmator 9 and on into mixing chamber 29. This charging line 41 may be provided with valves 43 and 44 and by-pass line 45 so that the charging stock may be fed directly into the top of dephlegmator 9 through nozzle 46 and reach mixing chamber 29 through reflux leg 34.

It is a well known fact today that in the cracking of petroleum oils certain disadvantages are experienced in passing oil to be cracked once through the cracking zone without the return of the reflux condensate in that when any substantial cracking is produced the cracking tubes quickly fill up with a heavy carbon-like substance and coke and even if the charging stock is continuously supplied with a reflux condensate and passed through the cracking zone, in order to obtain a large yield of lighter distillates, this coke or coke-

like material is necessarily deposited in the expansion chamber.

In order that this coke or coke-like substance may be done away with and the residuum retained in liquid form of good commercial value, the process may be run as follows:

In starting, the charging stock is fed through line 41 into mixing chamber 29, either through dephlegmator 9 or exchanger 42 and is picked up by pump 1, and through line 2 is sent through cracking tubes 3 where it is heated to the desired cracking temperature, which, in this process, need not be as high as 850 or 900° F., but wherein a temperature of 15 750 or 800° F. will produce the desired results. The heated charging stock is then discharged into expansion chamber 6 where a separation or reaction takes place, the lighter vapors going through vapor line 7 into dephlegmator 9 and the heavier portion going out through line 30, with valve 33 closed, and into line 28, and then into mixing chamber 29. As the vapors from the vapor line reach dephlegmator 9 they are separated into lighter vapors which pass out through vapor line 10 and on into receiver 15, after being condensed in condenser 12, and into heavier fractions which drop to the bottom as reflux condensate, being withdrawn through line 34 25 and passed to mixing chamber 29.

As the process continues the residuum from expansion chamber 6, the reflux from dephlegmator 9, and the charging stock passed through line 41 all come together in mixing chamber 29 where they may or may not be given mechanical agitation by means of stirrer 35. As pump 1 continues to pick up this material and circulate it through cracking tubes 3, the temperature gradually increases and it is so treated until vapors having a desired end boiling point are coming from the top of dephlegmator 9. As the process progresses and the liquid level in the expansion chamber 6 rises, the residuum may be 40 drawn off and into mixing chamber 29 through either of valves 25, 26 or 27 and into mixing chamber by means of line 28.

If this process continues as so far described, certain results may be obtained, but in a much 50 shorter period of time the cracking tubes 3 may clog up with coke and the accumulation of coke in expansion chamber 6 may prevent the withdrawal of residuum and constitute the end of a run. To overcome this objection, pump 39 is started and a portion of the oil in the mixing chamber 29, which is at a temperature far below that of the oil in the transfer line 5 is fed into expansion chamber 6 and comes in contact with the residuum or heavier 55 ends resulting from the separation of the oil in the expansion chamber and so regulates the nature, viscosity, and character of this residuum as to keep it in liquid form and continually allow same or a portion of same to flow 60 back to mixing chamber 29 where it is mixed 65

with reflux and charging stock for further cracking in coil 3.

As this residuum becomes heavier a portion of same may be withdrawn through line 30 at the bottom of expansion chamber 6 and by regulating valves 31 and 33 may be drawn off through line 32 into a fuel oil storage tank (not shown).

By operating the process as above described, the oil to be treated can be subjected 75 to an increased number of times to milder cracking conditions as it passes through cracking tubes 3 and to a greater agitation in the ring or cycle, which prevents the accumulation of undesirable coke and also allows a greater 80 yield of lighter distillates or gasoline without forming any substantial amount of coke and forming a residuum salable as commercial fuel oil.

The process may be operated with predetermined superatmospheric pressures from 85 three to several hundred pounds on the cracking tube 3, expansion chamber 6, dephlegmator 9, and receiver 15 by the manipulation of valves 11, 14 and 17, or differential pressures 90 may be maintained.

I claim as my invention:

1. A process of hydrocarbon oil conversion comprising subjecting oil to cracking conditions of temperature and superatmospheric pressure in a heating zone to cause substantial vaporization, passing the heated oil to a vapor separating zone and there separating the vapors, subjecting the vapors to reflux condensation, separately condensing and collecting the uncondensed vapors subsequent to reflux condensation, removing from the vapor separating zone regulated portions of non-vaporized residue and passing same to an enlarged mixing zone wherein a substantial body accumulates, removing from the reflux condensing zone regulated portions of reflux condensate and passing same to said mixing zone wherein a substantial body thereof accumulates and mixes with said substantial body of non-vaporized residue, and removing from said mixing zone regulated portions of said mixture and directing same directly and without passage through said heating zone to said vapor separating zone where said mixture mixes with the non-vaporized residue accumulated in said vapor separating zone.

2. A process of hydrocarbon oil conversion comprising subjecting oil to cracking conditions of temperature and superatmospheric pressure in a heating zone to cause substantial vaporization, passing the heated oil to a vapor separating zone and there separating the vapors, subjecting the vapors to reflux condensation, separately condensing and collecting the uncondensed vapors subsequent to reflux condensation, removing from the vapor separating zone regulated portions of non-vaporized residue and passing same to a

- mixing zone, removing from the reflux condensing zone regulated portions of reflux condensate and passing same to said mixing zone where it mixes with said non-vaporized residue.
- 5 due, and removing from said mixing zone regulated portions of said mixture and passing same directly and without passage through said heating zone to said vapor separating zone at a point removed from the
- 10 heated oil introduction where said mixture mixes with the non-vaporized residue accumulated in said vapor separating zone and continuously withdrawing from said vapor separating zone regulated portions of the
- 15 heavy non-vaporized residue and isolating same from the system.
3. A process of hydrocarbon oil conversion comprising subjecting oil to cracking conditions of temperature and superatmospheric pressure in a heating zone to cause substantial vaporization, passing the heated oil to a vapor separating zone and there separating the vapors, subjecting same to reflux condensation, separately condensing and collecting the uncondensed vapors subsequent to reflux condensation, removing from the vapor separating zone regulated portions of non-vaporized residue and passing same to a mixing zone, removing from the reflux condensing zone regulated portions of reflux condensate and passing same to said mixing zone where it mixes with said non-vaporized residue, and removing from said mixing zone regulated portions of said mixture and directing same to said vapor separating zone where said mixture mixes with the non-vaporized residue accumulated in said vapor separating zone, in simultaneously and separately removing from said mixing zone controlled quantities of said mixture and directing same to said heating zone, and mixing with the latter controlled quantities of fresh charging stock.
- 20 25 30 35 40 45 50 55 60 65
6. A process of hydrocarbon oil conversion comprising subjecting oil to cracking conditions of temperature and superatmospheric pressure in a heating zone to cause substantial vaporization, passing the heated oil to a vapor separating zone and there separating the vapors, subjecting the vapors to reflux condensation, separately condensing and collecting the uncondensed vapors subsequent to reflux condensation, removing from the vapor separating zone regulated portions of non-vaporized residue and passing same to a mixing zone, removing from the reflux condensing zone regulated portions of reflux condensate and passing same to said mixing zone where it mixes with said non-vaporized residue, and removing from said mixing zone regulated portions of said mixture and directing same to said vapor separating zone where said mixture mixes with the non-vaporized residue accumulated in said vapor separating zone, the portions of said mixture from the mixing zone being introduced to the vapor separating zone at a lower temperature than the temperature of the hydrocarbons within the vapor separating zone.
7. A process of hydrocarbon oil conversion comprising subjecting oil to cracking conditions of temperature and superatmospheric pressure in a heating zone to cause substantial vaporization, passing the heated oil to a vapor separating zone and there separating the vapors, subjecting same to reflux condensation, separately condensing and collecting the uncondensed vapors subsequent to reflux condensation, remov-
- 70 75 80 85 90 95 100 105 110 115 120 125 130

ing from the vapor separating zone regulated portions of non-vaporized residue and passing same to a mixing zone, removing from the reflux condensing zone regulated portions of reflux condensate and passing same to said mixing zone where it mixes with said non-vaporized residue, and removing from said mixing zone regulated portions of said mixture and directing same to said vapor separating zone where said mixture mixes with the non-vaporized residue accumulated in said vapor separating zone returning other portions of said mixture to said heating zone, simultaneously removing from the mixing zone any released vapors and passing same to said dephlegmating zone and maintaining a lower pressure in said mixing zone than is maintained in said separating zone.

20 8. A process of hydrocarbon oil conversion which consists in passing the oil through a heating coil wherein it is heated to a cracking temperature under superatmospheric pressure, discharging the heated oil into an enlarged zone of reaction wherein vapors are evolved and separate from unvaporized oil, taking off the vapors and subjecting them to dephlegmation, passing the reflux condensate to a mixing zone, passing unvaporized oil from said zone of reaction to said mixing zone, returning vapors from said mixing zone to the dephlegmation step, removing regulated portions of said mixture from said mixing zone and introducing said portions to said zone of reaction apart from the discharge of heated oil thereinto.

9. A process of hydrocarbon oil conversion which consists in passing the oil through a heating coil wherein it is heated to a cracking temperature under superatmospheric pressure, discharging the heated oil into an enlarged zone of reaction wherein vapors are evolved and separate from unvaporized oil, taking off the vapors and subjecting them to dephlegmation, passing the reflux condensate to a mixing zone, passing unvaporized oil from said zone of reaction to said mixing zone, passing charging oil for the process in heat interchange with the vapors undergoing dephlegmation and then passing such charging oil to the mixing zone, removing regulated portions of said mixture from said mixing zone and introducing said portions to said zone of reaction apart from the discharge of heated oil thereinto.

10. A process of hydrocarbon oil conversion which consists in passing the oil through a heating coil wherein it is heated to a cracking temperature under superatmospheric pressure, discharging the heated oil into an enlarged zone of reaction wherein vapors are evolved and separate from unvaporized oil, taking off the vapors and subjecting them to dephlegmation, passing the reflux condensate to a mixing zone, passing the unvapor-

ized oil from said zone of reaction to said mixing zone, subjecting the contents of said mixing zone to agitation, removing regulated portions of said mixture from said mixing zone and introducing said portions to said zone of reaction apart from the discharge of heated oil thereinto.

11. A process for cracking hydrocarbon oil comprising passing the oil through a heating coil and thence to the first of serially connected enlarged chambers, delivering liquid oil from the first to the second enlarged chamber, taking off vapors from the second enlarged chamber, passing said vapors to a reflux condenser, introducing charging oil for the process and reflux condensate from said reflux condenser to said second enlarged chamber, maintaining a local cyclic circulation through said enlarged chambers by withdrawing oil from the second chamber and returning it directly to the first chamber and maintaining a second cyclic circulation through said heating coil and chambers by withdrawing additional oil from said second chamber and supplying the same to said heating coil.

12. A process for cracking hydrocarbon oil comprising passing the oil through a heating coil and thence to the first of serially connected enlarged chambers, taking off vapors therefrom, delivering liquid oil from the first to the second enlarged chamber, taking off vapors from the second enlarged chamber, passing said vapors from both chambers to a reflux condenser, introducing charging oil for the process and reflux condensate from said reflux condenser to said second enlarged chamber, maintaining a local cyclic circulation through said enlarged chambers by withdrawing oil from the second chamber and returning it directly to the first chamber and maintaining a second cyclic circulation through said heating coil and chambers by withdrawing additional oil from said second chamber and supplying the same to said heating coil.
